UNITED STATES PATENT OFFICE.

EUGEN SANDOW, OF LONDON, ENGLAND.

SPRING-GRIP DUMB-BELL.

1,308,259.

Specification of Letters Patent.

Patented July 1, 1919.

Application filed October 19, 1917. Serial No. 197,474.

To all whom it may concern:

Be it known that I, EUGEN SANDOW, a subject of His Majesty the King of Great Britain and Ireland, residing at London, England, have invented new and useful Improvements in Spring-Grip Dumb-Bells, of which the following is a specification.

This invention relates to spring grip dumb bells, chest expanders or like physical exercisers.

The object of this invention is to combine with a spring grip dumb bell or the like means for varying the effective length of the spring or springs so that it requires a varying amount of strength to overcome the resistance offered by the spring, and with means for visibly indicating the value of the strength required or the resistance offered, say in pounds, to extend or compress said spring or springs to the full extent. A further object consists in combining with the means referred to means for giving an audible indication when the full grip or movement has been made.

The present invention consists in the combination of means for varying the effective length of the spring or springs, with means for visibly indicating the value of the strength required to overcome the resistance offered by the spring or springs with or without means for giving an audible indication that the full grip or movement has been made.

According to this invention, coil springs whether adapted to be used under tension or compression may be arranged to have a part or parts of their coils put out of action by a projection in the form of a screw thread or threads adapted to enter between the coils either from inside or outside of same and support at least one complete coil of the spring, said projection forming a point for the coil to abut against or to pull from, which point may include any desired number of the coils according to the position in which it is set, the number varying according to the pull or pressure required to extend or compress that part of the coil in action.

The other end of the spring may work against a point adapted either to abut against or to pull from, or the spring at such end may be provided with a similar coil cutting out device to that above referred to.

In practice the separating device for the coils is preferably a single turn of a wedge shaped screw thread carried on an external or internal tube or rod or like part so arranged that it can be screwed to and from along the coil of the spring.

In the accompanying drawing which illustrates this invention, more particularly in connection with spring grip dumb bells:

Figures 1, 2 and 3 illustrate in longitudinal section some embodiments of the essential features of this invention and

Fig. 4 shows the invention, in longitudinal section, as applied to a dumb-bell.

In the example shown in Fig. 1, the spring is arranged in compression. The device comprises a rotatable tube 1, furnished with an internal screw thread 2 adapted to engage with the coils of the spring 3 located within the tube 1. One end of the spring 3 is attached at 4 to the end of a slidable rod or tube 5 arranged within the coils of the spring 3. The end of the spring 3 may carry or be formed as a pointer 6 adapted to contact with points or marks on the internal rod or tube 5, such pointer serving to show the extent of movement between the parts 1 and 5 and the compression of the spring 3.

In this form of my invention the tubes 1 and 5 are relatively fixed longitudinally in some supporting frame as for instance in a dumb bell, not shown, and keep this same relative position except when force is applied, such as the gripping action of the hand. On the release of the force applied the tubes 1 and 5 spring back to their former relative position. The pointer 6 cooperates with the transverse marks on the tube 5. As the member 1 is rotated in one direction it brings more coils of the spring within itself and since the members 1 and 5 are longitudinally immovable except under gripping action, as explained above, this brings the pointer 6 to the right, Fig. 1, as fewer coils of the spring will be left outside. In this manner the pointer 6 indicates the compression in the spring 3, which is proportional to the length contained within the member 1.

It will be seen that the greater the number of coils of the spring 3 located within the tube 1, the greater will be the resistance offered by the spring and the power required to separate the parts 1 and 5.

In the example shown in Fig. 2, the spring is arranged in tension. The device

comprises a rotatable rod or like part 7 furnished near each end with a screw thread 8, 9, adapted to engage with the coils of two surrounding springs 10, 11 respectively, 5 the opposite ends of said springs being engaged by pins 12, 13, carried by parts 14, 15, respectively slidably mounted on the ends of the part 7.

As in the construction shown in Fig. 1, 10 the springs 10, 11 may each be provided with a pointer 10^x, 11^x respectively adapted to co-act with points or marks on the part 7.

In this construction, the greater the number of coils of the springs 10 and 11 located 15 on the right and left respectively of the threads 8 and 9, that is, rendered inactive, the greater will be the resistance offered by the spring and the power required to separate the ends 14 and 15.

20 A second form of device in which a tension spring is employed is shown in Fig. 3 in which a single spring 16 is entirely enclosed within a rotatable tube 17 furnished with a thread 18. The outer end of the 25 spring 16 is attached to a hook or part 19 carried by a slidable part 20 surrounding one end of the tube 17. The part 19 is moved to extend the spring by the movement of some part of an apparatus to which 30 it is applied as in the other cases. As in the other forms means are provided for indicating the extent of movement of the moving parts.

In this case the tube 17 is provided with 35 a slot 21 through which the coils of the spring may be seen, the end coil of the spring co-acting with marks or points 22 on the tube 17.

Either of the devices above described may 40 be used in connection with a spring grip dumb-bell in which it is desired to regulate the strength required for the grip and to indicate the gripping strength applied, as well as to give an audible indication either 45 when the limit of grip compression is obtained or when the grip is relaxed, or both, and the application of the arrangement substantially as shown in Fig. 2, but with only one spring to a dumb-bell is shown in Fig. 4.

50 According to the example illustrated the handle portion is formed of two or more separated sections 23 so as to be compressible, and the ends 24 of each section are beveled and fit into end pieces 25, 26, provided with annular recesses each formed with a beveled surface 27, adapted to co-act with the beveled ends on the sections 23, the arrangement being such that any compression of the sections 23 tends to force the 55 end pieces 25, 26 apart.

Between the sections 23 and carried by the end piece 26 is a rotatable rod or part 28 having an external thread 29 of the form above referred to, said thread engaging the 60 coils of a spring 30 the outer end of which

is attached, such as by pins 31, to a part 32 slidably mounted on a reduced part of the rod 28.

Means are provided for rotating the rod 28 from one of the ends. In the device 70 illustrated such means comprises a spring controlled part 33, sunk in the end 26, arranged to engage a squared part 34 formed on the rod 28. The part 33 may be drawn out to afford a grip to the fingers and 75 pushed in again when the desired adjustment has been made.

The provisions for an audible signal may consist of a gong 35 located in a recess provided in the part 25, said gong being carried by the part 32 seated in the end 25. The part 32 also carries a spring shanked hammer 36 to which a pawl 37, having a limited movement in two directions, is pivoted, said pawl co-acting with a collar or 85 part 38 formed on or carried by the reduced part of the rod 28.

In operation, the compression of the sections 23 will cause the ends 25, 26, to separate against the resistance offered by the 90 spring, the end 25, part 32, gong 35 and hammer 36 moving to the left and the end 26 and collar 38 to the right, the tripping of the pawl 37 causes the hammer to strike the gong both when the parts move outwardly caused by compression, or move inwardly caused by relaxation of the pressure. 95

The rod carrying the screw thread is visible between the sections 23, and, if the rod 100 28 is provided with division marks, indicating say pounds pressure, and the end coil of the spring 30 is formed as a pointer 39, the amount of pressure exerted to extend the active portion of the spring, left free by 105 the position of the thread therein, will be seen by the position of the pointer and the indicator.

What I claim is:—

1. A spring grip dumb bell, having in 110 combination, a spring, means for varying the effective length of said spring, means for visibly indicating the value of the strength required to overcome the resistance offered by said spring, and means for giving an audible indication when the full grip has been given. 115

2. A spring grip dumb bell having in combination, a spring, means for varying the effective length of said spring, means 120 for visibly indicating the value of the strength required to overcome the resistance offered by said spring, compressible grip sections having beveled ends, slidably end pieces having beveled recesses receiving and co-acting with the ends of the grip sections, and controlled by the spring, and means for giving an audible indication when the desired extent of end movement has been attained by the slidably end pieces. 125

3. A spring grip dumb bell having in combination, a spring, means for varying the effective length of said spring, means for visibly indicating the value of the strength required to overcome the resistance offered by said spring, compressible grip sections having beveled ends, slidable end pieces having beveled recesses receiving and co-acting with the ends of the grip sections, and controlled by the spring, a gong located in a recess in one of the end pieces, and means operated through the spring for sounding the gong at a certain point of movement of the slidable end piece.
- 15 4. A physical exerciser in the form of a spring grip dumb bell, comprising in combination a rotatable inextensible part, a projection in the form of a screw thread formed on such part, a coiled spring adapted to engage with such projection, a part slidably mounted on one end of the rotatable inextensible part to which one end of the spring is connected, end pieces arranged to co-act with the rotatable inextensible part and with the slidable part mounted thereon respectively, two or more separated sections adapted to co-act with said end pieces so that any compression of the separated sections tends to force the end pieces apart, indicating points or marks provided on the rotatable inextensible part and a pointer
- 20
- 25
- 30

provided on the spring adapted to co-act therewith for the purpose of indicating the value of the strength required to overcome the resistance offered by the spring.

35

5. A physical exerciser in the form of a spring grip dumb bell, comprising in combination a rotatable inextensible part, a projection in the form of a screw thread formed on such part, a coiled spring adapted to engage with such projection, a part slidably mounted on one end of the rotatable inextensible part to which one end of the spring is connected, end pieces arranged to co-act with the rotatable inextensible parts and with the slidable part mounted thereon respectively, two or more separated sections adapted to co-act with said end pieces so that any compression of the separated sections tends to force the end pieces apart, indicating points or marks provided on the rotatable inextensible part, a pointer provided on the spring adapted to co-act therewith for the purpose of indicating the value of the strength required to overcome the resistance offered by the spring, and means for giving an audible indication when the full grip or movement has been given.

In witness whereof I have hereunto set my hand.

EUGEN SANDOW.
